UNITED STATES PATENT OFFICE.

JAMES J. HINDE, OF SANDUSKY, OHIO.

WRAPPER.

SPECIFICATION forming part of Letters Patent No. 761,172, dated May 31, 1904.

Application filed May 31, 1902. Serial No. 109,762. (No model.)

To all whom it may concern:

Be it known that I, JAMES J. HINDE, a citizen of the United States, residing at Sandusky, in the county of Erie and State of Ohio, have invented certain new and useful Improvements 5 in Wrappers, of which the following is a specification, reference being had therein to the accompanying drawings.

The invention relates to wrappers especially 10 designed for protecting for shipment bottles and other fragile articles.

It is the object of the invention to obtain a construction in which the article is more effectively guarded than with constructions 15 heretofore used; and to this end the invention consists in the construction as hereinafter described and claimed.

In the drawings, Figure 1 is a perspective view of a wrapper, showing the two sections 20 thereof as about to be engaged with each other. Fig. 2 is a cross-section through the wrapper as applied to the bottle.

Heretofore wrappers have been made of paper or other similar substance in the form 25 of corrugated tubes. Such a wrapper protects the article packed therein, as the corrugations form cushions on all sides of the article, which guard it from injury.

It is the object of the present construction 30 to increase the effectiveness of the wrapper by employing a plurality of corrugated tubes sleeved upon each other. It is obvious, however, that if these tubes were exactly similar in construction the corrugations of one would 35 fall into mesh with those of the other or oth-

ers, so that the cushioning effected would not be materially increased. To overcome this difficulty, I have devised a construction in which the corrugations of the different tubes are held out of mesh, so that the cushioning 40 effect of the wrapper is proportional to the number of tubes used.

As illustrated in the drawings, A is an inner wrapper, shown as having longitudinal corrugations formed therein.

B is an outer wrapper of a size to receive the wrapper A telescopically and also provided with longitudinal corrugations. The corrugations *a* of the wrapper A are, however, of different size from the corrugations 50 *b* of the wrapper B. Thus when the two sections are telescoped and arranged around the article, as illustrated in Fig. 2, the corrugations *a* and *b* are held out of mesh.

What I claim as my invention is— 55

1. A wrapper comprising a plurality of telescopic sections of corrugated tubing, the corrugations of the tubes varying in size, whereby they are held out of mesh.

2. A wrapper comprising two or more corrugated sections, the corrugations of the sections being arranged longitudinally thereof, and varying in size whereby they are held out of mesh. 60

In testimony whereof I affix my signature in 65 presence of two witnesses.

JAMES J. HINDE.
